(57) **CLAIM**

The ornamental design for an automotive protective pad, as shown and described.

DESCRIPTION

FIG. 1 shows a perspective view of an automotive protective pad showing our new design.

FIG. 2 shows a top plan view of an automotive protective pad.

FIG. 3 shows a bottom plan view thereof.

FIG. 4 shows a front side elevational view thereof.

FIG. 5 shows a rear side elevational view thereof.

FIG. 6 shows a right side elevational view thereof; and, FIG. 7 shows a left side elevational view thereof.

FIGS. 2-7 are shown on an enlarged scale as compared to FIG. 1. The dashed lines on the edge of the pad are understood to represent stitching.
